US00D723473S

(12) **United States Design Patent**
Hagarty

(10) **Patent No.:** **US D723,473 S**
(45) **Date of Patent:** **** Mar. 3, 2015**

(54) **JUNCTION BOX WITH CABLE KEEPERS**

(71) Applicant: **RANDL Industries, Inc.**, Spokane Valley, WA (US)

(72) Inventor: **Robert J. Hagarty**, Spokane, WA (US)

(73) Assignee: **RANDL Industries, Inc.**, Spokane, WA (US)

(**) Term: **14 Years**

(21) Appl. No.: **29/491,788**

(22) Filed: **May 23, 2014**

Related U.S. Application Data

(63) Continuation-in-part of application No. 29/487,306, filed on Apr. 7, 2014, and a continuation-in-part of application No. 29/486,897, filed on Apr. 3, 2014.

(57) **CLAIM**

The ornamental design for a junction box with cable keepers, as shown and described.

DESCRIPTION

FIG. 1 is a perspective view of a junction box with cable keepers in accordance with the present design;

FIG. 2 is a front view of the junction box with cable keepers shown in FIG. 1;

FIG. 3 is a rear view of the junction box with cable keepers shown in FIG. 1;

FIG. 4 is a plan view of the junction box with cable keepers shown in FIG. 1;

FIG. 5 is a bottom view of the junction box with cable keepers shown in FIG. 1;

FIG. 6 is a left side view of the junction box with cable keepers shown in FIG. 1; and,

FIG. 7 is a right side view of the junction box with cable keepers shown in FIG. 1.

In the drawings, the broken lines depict unclaimed subject matter only and form no part of the claimed design.
